UNITED STATES PATENT OFFICE.

JOHN J. BROPHY AND WINN E. BROUGHTON, OF PEABODY, MASSACHUSETTS, ASSIGNEES TO THE TURNER TANNING MACHINERY COMPANY, OF PEABODY, MASSACHUSETTS, A CORPORATION OF MAINE.

MACHINE FOR TREATING HIDES, SKINS, AND LEATHER.

Application filed May 25, 1922. Serial No. 563,617.

This invention relates to cutting machines and is herein disclosed as embodied in a shaving machine provided with a rotatable, bladed cylinder adapted to shave hides, skins and leather and with a rotary grinder reciprocated relatively to the bladed cylinder and operative to keep the blades of the cylinder sharp.

It is an object of the invention to provide a shaving machine capable of doing a superior grade of work which at the same time will have an increased output and efficiency and will be inexpensive to construct and maintain.

With this object in view, the bladed cylinder, which is characteristic of shaving machines of this type, is directly connected to a driving motor, the rotor of the motor being mounted upon the shaft of the cylinder.

This practically eliminates chattering and vibration of the bladed cylinder and, accordingly, produces superior work free from the objectionable markings of the skins which are a not infrequent incident of the shaving operation as performed by the machines of the prior art. The illustrated machine, in accordance with current practice, is also provided with a rotary grinder reciprocated lengthwise of the bladed cylinder and arranged to sharpen the blades of the cylinder.

In accordance with the present invention, this grinder also is directly connected to an electric motor arranged to reciprocate with the grinder and having its rotor mounted on or directly connected to the shaft of the grinder.

Since the other power-operated parts of the machine are driven from one of these motors, it follows that the machine constitutes a self-contained unit capable of being installed anywhere in a factory or tannery even though the building is not provided with shafting.

With the above and other objects and features in view, the invention will now be described with reference to the accompanying drawings and pointed out in the claims.

In the drawings:

Fig. 1 is a front elevation of a shaving machine embodying this invention.

Fig. 2, a plan of the machine shown in Fig. 1 with parts broken away.

Fig. 3, a side elevation looking toward the right in Fig. 2, and

Fig. 4, a side elevation looking toward the left in Fig. 2.

The shaving machine herein shown as embodying this invention is provided with a bed roll 10, a bladed cylinder 12, a grinding wheel 13 and a reciprocating carriage 14 for the latter, substantially as in machines of this character now commonly in use. In accordance with the present invention, the bladed cylinder 12 is driven by an electric motor 15 mounted on a bracket 16 attached to a side upright 17 of the framework of the machine.

The shaft 18 of the bladed cylinder 12 is extended through long bearings 19, 20 attached to the side uprights 17 of the framework of the machine, and said shaft has directly attached to it in any suitable manner, the rotor or armature of the motor 15.

The shaft 18 beyond the bearing 20 has mounted on it two pulleys 21, 22, the pulley 21 being connected by a belt 23 with a pulley 24 on the shaft 25, by means of which the carriage 14 carrying the grinding wheel 13 is reciprocated in a manner well understood and common to machines of this character.

The pulley 22 is connected by a belt 28 with a relatively large pulley 29 on a shaft 30 mounted in the framework and provided with a smaller pulley 31, see Fig. 4, which is connected by a belt 32 with a pulley 33 on the shaft of a rotary brush 34, which is located below and cooperates with the bladed cylinder 12 to keep the latter free from chips, dust, etc.

It will thus be seen that the electric motor 15 acts as a source of power for the bladed cylinder 12, for the reciprocating carriage 14 which carries the grinder, and for the brush 34.

Provision is made for rotating the grinding wheel 13 at a relatively high speed as its carriage 14 is reciprocated in a path parallel with the axis of the bladed cylinder 12. To this end, a relatively small electric motor 35 is supported in a bracket or frame 36 attached to the grinder carriage 14 and said motor has its rotor 37 mounted on the shaft 38 of the grinding wheel 13. The framework of the machine is provided with a suitable base 40 and the bed roll 10 is mounted in levers 41 which are operated by a foot treadle 42 to move the bed roll with the work

thereon with relation to the bladed cylinder 12, and the depth of the cut made by the bladed cylinder is controlled by the operator pressing more or less upon the treadle, 5 the same as in shaving machines now in use in tanneries or factories.

From the above description it will be seen that the bladed cylinder 12 is revolved at a relatively high speed by the electric motor 15 without vibration or chattering of the bladed cylinder 12, and as a result a superior grade of work is obtained, inasmuch as marking or otherwise injuring the work by chattering of the bladed cylinder is avoided. 15 Also the relatively high speed of the bladed cylinder enables a greater number of skins to be shaved in a given time.

Furthermore it will be observed that each machine is a self contained unit, having its 20 own motive power and is therefore capable of being placed in any suitable or desired room or place in a factory or tannery, as its operation does not depend upon the usual shafting. The electric motors 15, 35 are 25 supplied with current in any suitable or known manner.

It will also be observed that by directly driving the bladed cylinder 12 and the grinding wheel 13 by the electric motors 15 and 30 35 respectively, which are supported by the framework of the machine, and by utilizing the shaft of the bladed cylinder for driving the shaft which effects reciprocation of the carriage carrying the grinding wheel, and 35 also for driving the rotary brush for the bladed cylinder, the machine is materially simplified and its cost of construction and maintenance materially reduced.

One embodiment of the invention is herein shown, but it is not desired to limit the invention to the particular construction shown. 40

Claims:

1. In a machine of the character described, in combination, a bed roll to support the 45 hide, skin or leather operated upon, a bladed cylinder co-operating therewith and provided with a shaft, a framework having bearings through which said shaft is extended, an electric motor supported by said framework and having its rotor directly connected with one end of said shaft to rotate the bladed cylinder, a pulley mounted on the other end of said shaft, a grinding wheel cooperating with said bladed cylinder and provided with a shaft, a reciprocating carriage, an electric motor mounted on said carriage and having its rotor directly connected with the shaft of said grinding wheel, a shaft for effecting reciprocation of said carriage, and a pulley on the last mentioned shaft connected with the pulley on the shaft of the bladed cylinder.

2. In a machine of the character described, in combination, a bed roll to support the 55 hide, skin or leather, a bladed cylinder co-

operating therewith and provided with a shaft, a framework having bearings through which said shaft is extended, an electric motor supported by said framework and having its rotor directly connected with one end 70 of said shaft to rotate the bladed cylinder, a pulley mounted on the other end of said shaft, a grinding wheel cooperating with said bladed cylinder and provided with a shaft, a reciprocating carriage, an electric motor mounted on said carriage and having its rotor directly connected with the shaft of 75 said grinding wheel, a shaft for effecting reciprocation of said carriage, a pulley on the last mentioned shaft connected with the pulley on the shaft of the bladed cylinder, a rotary brush cooperating with said bladed cylinder, and means connecting said brush with the shaft of the bladed cylinder to be driven thereby. 80

3. In a machine of the character described, in combination, a bed roll, a bladed cylinder cooperating therewith, a grinding wheel cooperating with the bladed cylinder, a reciprocating carriage for said grinding wheel, an electric motor mounted on said carriage to reciprocate therewith and directly connected with said grinding wheel to rotate the latter, a framework to support said bladed cylinder and said carriage, an electric motor mounted on said framework and having its rotor directly connected with the bladed cylinder to rotate the same, and means for connecting the bladed cylinder with said carriage to effect reciprocation of the latter by rotation of said cylinder. 95

4. In a machine of the character described, in combination, a bed roll, a bladed cylinder cooperating therewith, a grinding wheel cooperating with the bladed cylinder, a reciprocating carriage for said grinding wheel, an electric motor mounted on said carriage to reciprocate therewith and directly connected with said grinding wheel to rotate the latter, a framework to support said bladed cylinder and said carriage, and an electric motor mounted on said framework and having its rotor directly connected with the bladed cylinder to rotate the same. 110

5. A machine for operating upon skins having, in combination, a frame, a shaft rotatably mounted in bearings carried by the frame, a bladed cylinder upon the shaft, an electric motor supported by the frame having its rotor directly connected with the shaft to rotate the bladed cylinder, a bed roll co-operating with the bladed cylinder to support a skin to be operated upon, and means for varying the relative position of the bed roll and the bladed cylinder to vary the depth of the cut made by the bladed cylinder in the skin carried by the bed roll. 120

6. In a machine of the character described, in combination, a bladed cylinder, a 125

grinding wheel cooperating therewith and provided with a shaft, a reciprocating carriage in which said shaft is mounted, and an electric motor mounted on said reciprocating carriage and having its rotor directly connected with said shaft to rotate it and said grinding wheel.

7. A machine for operating upon skins having, in combination, a framework, a shaft mounted in bearings carried thereby, a bladed cylinder mounted upon the shaft, an electric motor carried by said framework and having its rotor mounted upon said shaft, a bed roll arranged to present a skin to be operated upon to the bladed cylinder, and a treadle controlled mounting for the bed roll whereby the bed roll may be moved toward or from the bladed cylinder to vary the depth of the cut made by the bladed cylinder in the skin.

8. In a machine of the character described, in combination, a bed roll, a bladed cylinder co-operating therewith, an electric

motor having its rotor directly connected with the bladed cylinder to rotate the same, 25 a grinding wheel co-operating with the bladed cylinder to sharpen said cylinder, a reciprocating carriage carrying said grinding wheel, an electric motor mounted on said carriage reciprocating therewith and directly connected with said grinding wheel to rotate the latter, a rotary brush arranged to clean said bladed cylinder, and means for rotating said brush.

9. A machine for operating upon skins 35 having, in combination, a frame, a shaft rotatably mounted in bearings carried by the frame, a cutter upon the shaft, an electric motor having its rotor directly connected to the shaft to rotate the cutter, and a grinder 40 arranged to co-operate with the cutter to sharpen the cutter.

In testimony whereof, we have signed our names to this specification.

JOHN J. BROPHY.

WINN E. BROUGHTON.
